UNITED STATES PATENT OFFICE

EDWARD LINDLEY BOWLES, OF WELLESLEY FARMS, MASSACHUSETTS

DIRIGIBLE DOCK

Application filed September 6, 1929. Serial No. 390,744.

The present invention relates to hangars or docks, and particularly to hangars or docks designed for the housing of dirigibles.

In the interest of economy, hangars or docks of the above-described character should be built as small as possible. This consideration must, however, yield to the fact that, if too little space is provided between the vertically disposed, projecting members of the hangar and the ship, the bag is liable to scrape against these members when the ship is entering or leaving the hangar, or to contact with them as the bag sways back and forth in the hangar. As the members are usually constituted of rough-steel truss elements, there is danger of ripping or otherwise injuring the bag.

An object of the present invention is to reduce the size of hangars of the above-described character while eliminating danger of injury to the dirigible bag. Other objects will be explained hereinafter, and will be particularly pointed out in the appended claims.

The invention will be explained in connection with the accompanying drawing, in which Fig. 1 is a vertical transverse section of a hangar, showing a dirigible housed therein; Fig. 2 is a fragmentary view upon a larger scale; Figs. 3 and 4 are fragmentary views showing modifications; and Fig. 5 is a section taken upon the line 5—5 of Fig. 1, looking in the direction of the arrows.

The dirigible 2 is shown in Fig. 1 disposed adjacent to a truss element, the inner portion 4 of which may consist of a huge, vertically disposed, fabricating constructional, rough-steel, rigid element. With the space between the ship 2 and this vertical member 4 small, there is danger, when the ship moves, of contact between the bag 6 and the member 4, and such contact may result in ripping or otherwise injuring the bag 6.

A protecting element 5 is shown disposed between the vertical rigid and rough element 4 and the bag 6. Preferably, each vertical member near the ship is provided with a strip 5. The strip 5 may consist of a band or strip of canvas or other flexible material or fabric supported between blocks 8 and 10. These blocks hold it away from the vertical mem-

ber 4. The element 5 may be stretched any degree of tautness; either by first doing so, by some well known mechanical means, and then securing the strip 5 to the supports 8 and 10; or by having the strips secured at one end and have a tension maintaining device, such as a spring 11 arrangement at the other, Fig. 3, or by having such an arrangement 11, 12 at both ends, Fig. 4. By having the strip 5 of the proper degree of tautness and resiliency, and having it of material which would not injure the bag 6 by contact, a pad or flexible protection is thus afforded for the bag 6. During the movement of the ship into or out of the hangar, or during its swaying movement when moored in the hangar, contact with the band 5 is of a gentle nature that could not cause injury to the bag 6. The band 5 gives or yields to the pressure of the bag, the bag yields and there are no rough surfaces in contact.

Modifications will obviously occur to persons skilled in the art, and all such are considered to fall within the spirit and scope of the present invention, as defined in the appended claims.

What is claimed is:

1. A dirigible hangar having an interior wall adjacent to which the bag of the dirigible is adapted to be disposed, the wall having a plurality of separated, rigid members disposed transversely of the bag and against which the bag is liable to contact, and a protecting element disposed between the wall and the bag for protecting the bag from damage by contact with the wall, the elements being of material that will not injure the bag by such contact.

2. A dirigible hangar having an interior wall adjacent to which the bag of the dirigible is adapted to be disposed, the wall having a plurality of separated, rigid members disposed transversely of the bag and against which the bag is liable to contact, and a flexible strip vertically disposed between the member and the bag.

3. A dirigible hangar having an interior wall adjacent to which the bag of the dirigible is adapted to be disposed, the wall having a plurality of separated, rigid members dis-

posed transversely of the bag and against which the bag is liable to contact, and a fabric strip stretched vertically between the member and the bag.

4. A dirigible hangar having an interior wall adjacent to which the bag of the dirigible is adapted to be disposed, the wall having a plurality of separated, rigid members disposed transversely of the bag and against which the bag is liable to contact, each rigid member having an upper and a lower block respectively disposed in substantial vertical alinement near the upper and the lower portions of the bag, and a flexible strip attached 10 to the blocks, the blocks maintaining the strip separated from the member.

5. A dirigible hangar having an interior wall adjacent to which the bag of the dirigible is adapted to be disposed, the wall having 20 a plurality of separated, rigid members disposed transversely of the bag and against which the bag is liable to contact, each rigid member having an upper and a lower block respectively disposed in substantial vertical alinement near the upper and the lower portions of the bag, a spring secured to one of 25 the blocks, and a flexible strip attached to the

spring and the other block, the spring maintaining the strip stretched and separated from the member.

6. A dirigible hangar having an interior wall adjacent to which the bag of the dirigible is adapted to be disposed, the wall having a plurality of separated, rigid members disposed transversely of the bag and against which the bag is liable to contact, each rigid member having an upper and a lower block 70 respectively disposed in substantial vertical alinement near the upper and the lower portions of the bag, a spring secured to each block, and a flexible strip attached to the springs, the springs maintaining the strip 75 stretched and separated from the member.

7. A dirigible hangar having an interior wall adjacent to which the bag of the dirigible is adapted to be disposed and against which the bag is liable to contact, and yielding means disposed between the wall and the bag for protecting the bag from damage by contact with the wall, the yielding means being of material that will not injure the bag 80 by such contact.
